(57) **CLAIM**

The ornamental design for a power tool, as shown and described.

DESCRIPTION

The entire contents of U.S. application Ser. No. 29/731,632, filed on Apr. 16, 2020, are incorporated herein by reference. FIG. 1 is a front, top, right side perspective view of a power tool showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front elevational view thereof; and,

FIG. 8 is a rear, top, right side perspective view thereof.

The broken lines in the drawings illustrate portions of the power tool that form no part of the claimed design.

1 Claim, 6 Drawing Sheets
